WELL CEMENTING APPARATUS

James V. Johnson, San Marino, Calif., assignor to
 Baker Oil Tools, Inc., Vernon, Calif., a corpora-
 tion of California

Application August 23, 1945, Serial No. 612,201

21 Claims. (Cl. 166—1)

1

This invention relates to apparatus particularly useful in the cementing of casings, liners and similar conduits in well bores.

It is an object of the present invention to provide an improved casing apparatus capable of allowing circulating fluid to be discharged through the lower end of a casing string, but which, nevertheless, can positively prevent cementitious materials from being deposited below such lower end either from within or externally along the apparatus.

A further object of the invention is to provide an improved apparatus for preventing cement slurry from moving, either internally or externally of the casing, below the general location of the casing cement discharge point, without impeding free up and down movement of the casing string prior to performance of the cementing operation.

Yet another object of the invention is to provide an improved simple and compact device for releasably securing an annular barrier in retracted position against a well casing member.

Still a further object of the invention is to provide an apparatus embodying an improved device for controlling casing cementing ports and the expansion of an annular barrier against the wall of a well bore.

This invention has other objects that will become apparent from a consideration of the embodiment shown in the drawings accompanying and forming part of the present specification. This form will now be described in detail to illustrate the general principles of the invention, but it is to be understood that such detailed description is not to be taken in a limited sense, since the scope of the invention is best defined by the claims appended hereto.

Referring to the drawings:

Figure 1 is a longitudinal view, partly in section and partly in elevation, of the apparatus with its parts in position for longitudinal movement in both directions within a well bore;

Figure 2 is a longitudinal section similar to Figure 1, disclosing the apparatus in condition for cementing the casing within a well bore;

Figure 3 is an enlarged partial longitudinal section of the annular barrier or basket retaining and releasing mechanism, in the position disclosed in Figure 1;

Figure 4 is a cross section taken along the line 4—4 in Figure 3, and

Figure 5 is a side elevation of the apparatus as seen from the right of Figure 4.

In the example of the invention illustrated in

2

the drawings, the apparatus comprises a casing shoe or collar A and an annular barrier in the form of a metal "petal" basket B, whose lower end 10 is welded or otherwise secured to the tubular member 11 of the shoe below its lateral outlets or ports 12. The shoe forms the lowermost part of a casing string by being attached to an upper adjacent casing string C.

The tubular member 11 contains a tubular body 13 whose spaced lower and upper ends 14, 15 engage the inner wall of the tubular member, with the upper head end 15 threaded on the intervening reduced medial portion 16 of the body. Leakage between the ends of the body and the tubular member is prevented in both directions by engagement of suitable side seals 17, 17 on the body ends 14, 15 with the wall of the member. The body 13 is prevented from moving longitudinally within the tubular member 11 by engagement of its lower end 14 with a ball stop 18 and its head end 15 with a shoulder 19 projecting inwardly from the tubular member. The ball stop 18 is held in its upper position against the lower end of the body by a cementitious plug 20 cast within the lower portion of the tubular member, which has a rounded nose 20a to serve as a guide for the shoe during its lowering through the hole. The ball stop 18 has inwardly projecting radial fingers 21 to support a buoyant back pressure ball valve member 22 when circulating fluid is pumped down through the casing and its shoe. This ball is movable upwardly into engagement with a valve seat 23 in the lower end 14 of the body during lowering of the casing through the fluid in the hole.

The tubular body has a plurality of ports or lateral openings 24 establishing communication between its interior and an annular chamber 25 formed between the medial portion 16 of the body and the tubular member 11. Fluids may flow from the body interior through its ports 24 into the chamber 25, for discharge through the tubular member ports 12 to the exterior of the shoe. Return flow is prevented by a back pressure valve 26 disposed over the exterior of the body ports 24. Such back pressure valve may be in the form of a flexible sleeve, of rubber or similar material, whose upper end is clamped between the medial portion 16 of the body and the head 15, and whose lower end is free to flex outwardly to open position under the hydraulic action of the fluid passing outwardly through the body ports 24. Any tendency for fluids to return into these ports presses the flexible sleeve 26 in leakproof port closing relation against the exterior of the body.

Outward passage of fluids through the body ports 24 is prevented initially by a sleeve valve 27 positioned within the body and disposed over its ports. One or more shear screws 28 extending through the body and threaded into the upper end of the sleeve valve 27 hold the latter in such port closing position. Suitable side seals 29, 29 may be mounted on the exterior of the sleeve 27 on opposite sides of the ports 24 to preclude any possibility of leakage between the sleeve and body. Upon shearing of the screws 28, the sleeve valve 27 is moved downwardly to a position below the ports 24, opening the latter to outward passage of fluids.

The annular barrier B, or metal "petal" basket, is of the general type described in United States Patent No. 2,117,538. It consists essentially of a plurality of longitudinally extending, circumferentially spaced leaf springs 30 secured to the exterior of overlapping basket "petals" 31. The springs and "petals" extend upwardly from the point of spring attachment at the lower end of the shoe over the ported area of the tubular member, the upper ends 30a of the leaf springs projecting longitudinally beyond the upper ends of the "petals" 31 and being bowed inwardly when unrestrained to space the upper ends of the "petals" from the shoe and cause the basket B to assume a general frusto-conical or bucket shape. The unrestrained bowed shape of the leaf springs 30 provides an inherent tendency for the basket to expand outwardly when retracted against the shoe.

The basket is held initially in retracted position by a band or strap 32 encompassing the bowed portions 30a of the leaf springs 30 above the upper ends of the "petals" 31, straightening such portions and clamping them, together with the "petals" and remainder of the springs, against the exterior of the shoe A. A bolt 33 extends through and between overlapping bifurcated ends 32a of the strap, through an opening 34 in the tubular member, and into a lateral cylinder 35, where the inner end of the bolt 33 is secured, as by threading, to an enlarged piston end 36 of the shear screw 28 disposed within the cylinder 35. Leakage between the exterior of the piston 36 and cylinder wall is prevented by a suitable piston ring 37 disposed within a piston groove 38. The head 39 of the bolt engages and clamps against a washer 40 which forces the bifurcated ends 32a of the strap inwardly around side edges 30b of the leaf springs 30, effecting inward crimping of the strap ends 32a, to prevent their circumferential movement along the casing shoe A to basket releasing position. This crimping action can occur since the widths of the bolt head 39 and washer 40 are less than the space between the adjacent retracted leaf springs 30 (see Figure 4).

The apparatus is secured to the lowermost casing section C of the casing string with its parts disposed in the relationship shown in Figure 1, wherein the shear screw 28 holds the sleeve valve 27 in closed position over the body ports 24 and the bolt 33 is secured to the shear screw to clamp the strap 32, leaf springs 30, and "petals" 31 in retracted position against the shoe A. During lowering of the casing string through the fluid in the casing, the back pressure ball valve 22 engages its companion seat 23 and permits floating of the casing in the hole to the desired depth. If any sand bridges or obstructions are encountered during the lowering operation, washing fluid can be pumped down the

casing and all of it will be forced to pass axially through the shoe for ejection from the lower end of its plug 20 onto the sand bridge, to flush it from the hole. After the casing string has been lowered to the desired point, circulating fluid may be pumped down the casing string for the purpose of conditioning the hole. It is to be noted that the annular barrier or basket B is in retracted position, which permits the casing string to be moved up and down during the circulating operation, as desired, without any danger of damaging the basket parts.

After the hole has been properly conditioned, a tripping or bridging member, which can be in the form of a ball 41, is pumped or otherwise allowed to gravitate through the fluid in the casing until it engages a seat 42 at the upper end of the sleeve valve 27, closing the central passage through the body. The fluid pressure in the casing is then increased to a predetermined degree to shear the screw 28 and move the sleeve valve 27 downwardly within the body against the body shoulder 43 to port opening position. The shearing of the screw 28 also releases the piston 36 and its attached bolt 33, permitting their lateral movement in an outward direction and removal of the clamping action of the bolt head 39 and washer 40 from the crimped ends 32a of the strap 32. This removal of restraint from the strap releases it from the leaf springs 30 and permits the latter to inherently assume their outwardly bowed condition, expanding the upper ends of the "petals" 31 against the wall of the well bore and forming the annular barrier into its normal frusto-conical shape (as in Figure 2). The tendency of the springs 30 to assume their normal bowed position produces sufficient springlike force by itself to release the crimped ends 32a of the strap from between the leaf springs 30 upon shearing of the screw 28, to allow unrestrained outward expansion of the basket against the wall of the well bore. This action is supplemented, if need be, by the strap itself, which may be made of a springlike material (such as box strapping) with a tendency to assume a more or less straight line condition, rather than retain its circular shape around the basket. The tendency for the strap to straighten upon outward displacement of the bolt head 39 and washer 40 would pull the crimped ends 32a from the leaf springs 30, and allow the latter, with their attached overlapping "petals," to expand against the wall of the hole. The releasing action is also assisted by fluid pressure in the casing passing into the cylinder 35 and acting on the inner end of the piston 36 to force it within the cylinder toward the wall of the tubular member 11. Since the bolt 33 is secured to the piston, its head 39 will also be removed in an outward direction completely from engagement with the washer 40, which, in turn, is freed from crimping engagement with the bifurcated ends 32a of the strap 32.

With the ports 24 in open position and the basket B expanded against the wall of the hole (as in Figure 2), cement slurry may be pumped down the casing string for outward passage through the body ports 24, displacing the back pressure valve 26 to one side in order to enter the annular chamber 25, from where it flows through the outer ports 12 to the exterior of the casing string above the point of welded attachment of the basket to the shoe, passing upwardly through the annulus around the casing string to the desired elevation. Return flow of the slurry into the casing string is prevented by the back pres-

sure valve 26. Such slurry cannot flow back to the interior of the casing through the bolt opening 34, because of the slidable sealing action of the piston 36 in the cylinder 35, which also prevents passage of fluids in the other direction between the interior and exterior of the shoe.

The closing action of the bridging ball 41 over the central passage through the sleeve valve 27 prevents passage of cement slurry centrally through the shoe A for ejection from its lower end, and the annular barrier B around the shoe prevents the cement slurry deposited behind the casing from dropping down below the shoe. Any producing zone that might be present below the shoe is, therefore, protected from contamination by cement slurry.

It is apparent that a well cementing apparatus has been provided which permits concentrated jetting action of circulating fluid during the well washing operation and its free circulation around the casing. Prior to the cementing operation the casing can be moved longitudinally in both directions through the well hole without subjecting the annular barrier to damage. After the hole is in condition for cementing, the cementitious material is prevented from passing down below the shoe either from within or externally of the casing, to prevent cement contamination of the formation below the shoe, while insuring that an effective cementitious bond is obtained between the casing string and the wall of the hole above the lower end of the shoe.

I claim:

1. An apparatus of the character described including tubular means having a port and adapted to form part of a casing string, an expandable annular barrier mounted on and surrounding said tubular means to form a circumferentially continuous annular barrier between said tubular means and the wall of a surrounding well bore, shiftable means within said tubular means for controlling fluid flow through said port, and releasable means interconnecting said shiftable means and barrier for releasably holding said shiftable means in closed position with respect to said port and for releasably holding said barrier in retracted position on said tubular means.

2. An apparatus of the character described including tubular means having a port and adapted to form part of a casing string, an inherently expandable annular barrier mounted on and surrounding said tubular means to form a circumferentially continuous annular barrier between said tubular means and the wall of a surrounding well bore, means within said tubular means for controlling fluid flow through said port, and means engageable with said barrier and comprising instrumentalities passing laterally through said tubular means, said instrumentalities being engageable with said controlling means for releasably holding said barrier in retracted position on said tubular means.

3. An apparatus of the character described including tubular means having a port and adapted to form part of a casing string, an outwardly expandable annular barrier mounted on and surrounding said tubular means to form a circumferentially continuous annular barrier between said tubular means and the wall of a surrounding well bore, shiftable means for controlling fluid flow through said port, means engageable with said barrier comprising instrumentalities releasably attached to said controlling means for holding said barrier in retracted position on said tubular means, and means movable downwardly

through said casing string into engagement with said controlling means to shift said shiftable means and effect release of said instrumentalities from said controlling means and permit outward expansion of said barrier from its retracted position.

4. An apparatus of the character described including tubular means having a port and adapted to form part of a casing string, an outwardly expandable annular barrier mounted on and surrounding said tubular means to form a circumferentially continuous annular barrier between said tubular means and the wall of a surrounding well bore, shiftable means for controlling fluid flow through said port, means attached to said controlling means for holding said controlling means in closed position over said port, means secured to said attaching means and engaging said barrier for holding said barrier in retracted position on said tubular means, and means movable downwardly through said casing string into engagement with said controlling means to shift said shiftable means and disrupt said attaching means and allow movement of said controlling means to port opening position and also permit outward expansion of said barrier from its retracted position.

5. An apparatus of the character described including tubular means adapted to form part of a casing string, an outwardly expandable annular barrier mounted on and surrounding said tubular means to form a circumferentially continuous annular barrier between said tubular means and the wall of a surrounding well bore, hydraulically operable means within said tubular means releasably secured to said barrier to hold said barrier in retracted position on said tubular means, said hydraulically operable means being mounted for movement transversely of said tubular means, releasable holding means engaging said hydraulically operable means to prevent release of said hydraulically operable means from said barrier, said hydraulically operable means being communicable with the interior of said tubular means to be subjected to and moved transversely by fluid under pressure within said tubular means to a position of release from said barrier when said holding means is disengaged from said hydraulically operable means.

6. An apparatus of the character described including tubular means adapted to form part of a casing string positioned in a well bore, an outwardly expandable annular barrier mounted on and surrounding said tubular means to form a circumferentially continuous annular bridge between said tubular means and wall of the well bore, a sleeve within said tubular means, means releasably secured to said sleeve and engaging said barrier for holding said annular barrier in retracted position on said tubular means, and means for releasing said holding means from said sleeve while said tubular means is positioned in said well bore.

7. An apparatus of the character described including tubular means adapted to form part of a casing string, an outwardly expandable annular barrier mounted on and surrounding said tubular means to form a circumferentially continuous annular barrier between said tubular means and the wall of a surrounding well bore, a sleeve within said tubular means, means releasably secured to said sleeve and engaging said barrier for holding said annular barrier in retracted position on said tubular means, and means adapted to be sent down said casing string into engagement with

7 said sleeve to shift said sleeve and effect release of said holding means from said sleeve.

8. An apparatus of the character described including tubular means having a port and adapted to form part of a casing string, an outwardly expansible annular barrier mounted on and surrounding said tubular means to form a circumferentially continuous annular barrier between said tubular means and the wall of a surrounding well bore, a sleeve movable within said tubular means for controlling fluid flow through said port, and means releasably secured to said sleeve and engaging said barrier for holding said sleeve in closed position over said port and said barrier in retracted position on said tubular means.

9. An apparatus of the character described including tubular means having a port and adapted to form part of a casing string, an outwardly expansible annular barrier mounted on and surrounding said tubular means to form a circumferentially continuous annular barrier between said tubular means and the wall of a surrounding well bore, a sleeve movable within said tubular means for controlling fluid flow through said port, and means comprising frangible instrumentalities secured to said sleeve and connected to said barrier for holding said sleeve in closed position over said port and said barrier in retracted position on said tubular means.

10. An apparatus of the character described including tubular means having a port and adapted to form part of a casing string, an outwardly expansible annular barrier mounted on and surrounding said tubular means to form a circumferentially continuous annular barrier between said tubular means and the wall of a surrounding well bore, a sleeve movable within said tubular means for controlling fluid flow through said port, means comprising frangible instrumentalities secured to said sleeve and connected to said barrier for holding said sleeve in closed position over said port and said barrier in retracted position on said tubular means, and means adapted to be sent down said casing string into engagement with said sleeve to close its central passage and allow hydraulic pressure to move said sleeve to disrupt said frangible instrumentalities, thereby moving said sleeve to port opening position and allowing outward expansion of said barrier from its retracted position.

11. An apparatus of the character described including tubular means adapted to form part of a casing string, an outwardly expansible annular barrier mounted on and surrounding said tubular means to form a circumferentially continuous annular barrier between said tubular means and the wall of a surrounding well bore, a sleeve movable within said tubular means, means comprising frangible instrumentalities secured to said sleeve and connected to said barrier for holding said barrier in retracted position on said tubular means, and means adapted to be sent down said casing string into engagement with said sleeve to close said central passage and allow hydraulic pressure to move said sleeve to disrupt said frangible instrumentalities, thereby allowing outward expansion of said barrier from its retracted position.

12. An apparatus of the character described including tubular means adapted to form part of a casing string, an expansible annular barrier mounted on and surrounding said tubular means to form a circumferentially continuous annular barrier between said tubular means and the wall

of a surrounding well bore, and means releasably secured to said barrier to hold said barrier in retracted position on said tubular means, said releasable means comprising cylinder and piston means movable laterally within said tubular means.

13. An apparatus of the character described including tubular means adapted to form part of a casing string, an expansible annular barrier mounted on and surrounding said tubular means to form a circumferentially continuous annular barrier between said tubular means and the wall of a surrounding well bore, means for releasably holding said barrier in retracted position on said tubular means comprising a strap encompassing said barrier, said holding means further including means secured to said strap and extending inwardly through said tubular means, and means providing a seal between said tubular means and said means secured to said strap to prevent leakage through said tubular means.

14. An apparatus of the character described including tubular means adapted to form part of a casing string, an expansible annular barrier mounted on and surrounding said tubular means to form a circumferentially continuous annular barrier between said tubular means and the wall of a surrounding well bore, a strap encompassing said barrier to hold said barrier in retracted position on said tubular means, means engaging said strap and extending inwardly through said tubular means, means providing a seal between said tubular means and said means secured to said strap to prevent leakage through said tubular means, and frangible means securing said strap engaging means in an inward position with respect to said tubular means to hold said strap in barrier retracting position.

15. An apparatus of the character described including tubular means having a port and adapted to form part of a casing string, an expansible annular barrier mounted on and surrounding said tubular means, a valve sleeve slideable within said tubular means for controlling fluid flow through said port, frangible means securing said sleeve in closed position over said port, a strap releasably encompassing said barrier, and means engaging said strap and secured to said frangible means to releasably hold said strap in position around said barrier wherein said strap holds said barrier retracted on said tubular means.

16. An apparatus of the character described including tubular means having a port and adapted to form part of a casing string, said tubular means having a lateral bore therein, an expansible annular barrier mounted on and surrounding said tubular means, a valve sleeve slideable within said tubular means for controlling fluid flow through said port, frangible means securing said sleeve in closed position over said port, a strap releasably encompassing said barrier, and releasable piston means within said bore secured to said frangible means and engageable with said strap to releasably hold said strap in position around said barrier wherein said strap holds said barrier in retracted position on said tubular means.

17. An apparatus of the character described including tubular means having a port and adapted to form part of a casing string, said tubular means having a lateral bore therein, an inherently expansible frusto-conical basket mounted on said tubular means, a valve sleeve slideable within said tubular means, frangible

means securing said valve sleeve in closed position over said port, a strap releasably encompassing said basket, a piston within said bore secured to said frangible means, and means secured to said piston and engaging said strap to releasably hold said strap contracted around said basket wherein said strap secures said basket in retracted position on said tubular means.

18. An apparatus of the character described including tubular means having a port and adapted to form part of a casing string, an inherently expandible annular barrier mounted on and surrounding said tubular means to form a circumferentially continuous annular barrier between said tubular means and the wall of a surrounding well bore, the lower portion of said barrier being in closed relation to said tubular means and the upper portion of said barrier being adapted to expand laterally outwardly from said tubular means, means within said tubular means for controlling fluid flow through said port, and means interconnecting said controlling means and the upper portion of said barrier for releasably holding said controlling means in closed position with respect to said port and for releasably holding said barrier in retracted position on said tubular means.

19. An apparatus of the character described including tubular means adapted to form part of a casing string positioned in a well bore, an inherently expandible annular barrier mounted on and surrounding said tubular means to form a circumferentially continuous annular barrier between said tubular means and the wall of a surrounding well bore, the lower portion of said barrier being in closed relation to said tubular means and the upper portion of said barrier being adapted to expand laterally outwardly from said tubular means, a sleeve within said tubular means, means releasably secured to said sleeve for holding said barrier in retracted position on said tubular means, and means for releasing said holding means from said sleeve while said tubular means is positioned in said well bore.

20. An apparatus of the character described including tubular means having a port and adapted to be connected to a casing string, an inherently expandible barrier mounted on and surrounding said tubular means to form a circumferentially continuous annular barrier between said tubular means and a surrounding well

bore, the lower portion of said barrier being in closed relation to said tubular means below said port and the upper portion of said barrier being adapted to expand laterally outwardly from said tubular means, movable means for controlling fluid flow through said port, and releasable means interconnecting said controlling means and barrier for positioning said controlling means with respect to said port and for releasably holding said upper portion of said barrier in retracted position on said tubular means.

21. An apparatus of the character described including tubular means having a port and adapted to be connected to a casing string, an inherently expandible barrier mounted on and surrounding said tubular means to form a circumferentially continuous annular barrier between said tubular means and a surrounding well bore, the lower portion of said barrier being in closed relation to said tubular means below said port and the upper portion of said barrier being adapted to expand laterally outwardly from said tubular means, movable means for controlling fluid flow through said port, releasable means interconnecting said controlling means and barrier for positioning said controlling means with respect to said port and for releasably holding said upper portion of said barrier in retracted position on said tubular means, said interconnecting means being releasable upon movement of said controlling means with respect to said tubular means, and means movable downwardly through said casing string into engagement with said controlling means to effect movement of said controlling means and release of said interconnecting means.
